[57] **CLAIM**

The ornamental design for a lockable carrier for bottles or similar article, as shown and described.

DESCRIPTION

FIG. 1 is a perspective view of a lockable carrier for bottles, or similar article showing my new design; FIG. 2 is a top plan view thereof;

FIG. 3 is a bottom plan view thereof; and

FIG. 4 is a front elevational view thereof. The design as shown has multifaceted symmetry about the longitudinal axis of the lockable carrier for bottles or similar article. The matter shown in dashed lines forms no part of the claimed design.

FIG. 1

FIG. 2

FIG. 3

FIG. 4
